CLAIM

We claim the ornamental design for a battery powered surgical screwdriver, as shown.

DESCRIPTION

FIG. 1 is a top plan view of a battery powered surgical screwdriver;

FIG. 2 is a bottom plan view of the battery powered surgical screwdriver;

FIG. 3 is a side plan view of the battery powered surgical screwdriver;

FIG. 4 is a front plan view of the battery powered surgical screwdriver;

FIG. 5 is a rear plan view of the battery powered surgical screwdriver; and,

FIG. 6 is a top, front perspective view of the battery powered surgical screwdriver.

The broken line showing details of the button in FIG. 6 and the indentation of FIGS. 2, 3 and 6 are for illustrative purposes only and forms no part of the claimed design.
